FOREIGN PATENT DOCUMENTS

WO WO 1994/029141 A1 12/1994

Primary Examiner — Sheryl Lane(74) *Attorney, Agent, or Firm* — Antoinette M. Tease(57) **CLAIM**

The ornamental design for a tarp stop as shown and described.

DESCRIPTION

FIG. 1 is a first bottom perspective view of a tarp stop showing the new design.

FIG. 2 is a side perspective view of a tarp stop showing the new design.

FIG. 3 is first side view of a tarp stop showing the new design.

FIG. 4 is a second side view of a tarp stop showing the new design.

FIG. 5 is a front view of a tarp stop showing the new design.

FIG. 6 is a rear view of a tarp stop showing the new design.

FIG. 7 is a bottom view of a tarp stop showing the new design.

FIG. 8 is a top view of a tarp stop showing the new design; and,

FIG. 9 is a second bottom perspective view of a tarp stop showing the new design.

The broken lines are for the purpose of illustrating unclaimed parts of the invention and/or showing environment and are not part of the claimed design.

1 Claim, 4 Drawing Sheets(56)
